APPARATUS FOR ELECTRICAL USES

Erwin E. Franz, Crawford, N. J., assignor to
Western Electric Company, Incorporated, New
York, N. Y., a corporation of New York

Application July 27, 1933, Serial No. 682,398

7 Claims. (CL 201-55)

This invention relates to apparatus for electrical uses and more particularly to continuously variable apparatus for use as resistances, rheostat elements, inductances, impedances, condensers and the like.

An object of the invention is to produce articles of the character described which may have a large range of variability of a characteristic property such as resistance, inductance, capacity, heat emission, etc., and/or which may be substantially continuously variable over the entire range.

With this and other objects in view one embodiment of the invention contemplates a core having an axial line in helical, spiral or other form and which comprises a non-terminating sequence of substantially toroidal segments joined to or abutting against each other and upon which a conductor of any desired length may be positioned thus enabling the construction of an unbroken element having any desired maximum capacity with respect to a given characteristic electrical property. A sliding contact member may be mounted in simple and effective fashion to slide along on the element and thus permit inclusion between one fixed end of the element and the sliding contact of any desired continuously adjustable amount of the conductor.

Other objects and characteristic features of the invention will appear from the following detailed description of an embodiment thereof taken in connection with the accompanying drawings in which like reference numerals are appended to identical parts in the several figures and in which

Fig. 1 is a semi-diagrammatic broken view in elevation partly in perspective and partly in section of a resistance coil embodying the invention;

Fig. 2 is a view thereof in left hand end elevation;

Fig. 3 is an exploded view of a pair of complementary core sections;

Fig. 4 is a view in vertical, longitudinal section on the plane 4-4-4-4 indicated in Fig. 1 to show the construction of the sliding contact;

Fig. 5 is a section on the line 5-5 of Fig. 4;

Fig. 6 is a diagrammatic plan view of another embodiment;

Fig. 7 is a central longitudinal section thereof;

Fig. 8 is a diagrammatic view in perspective of a third embodiment;

Fig. 9 is a side view thereof as mounted in an enclosing skeleton case, the case being shown in section;

Fig. 10 is a view similar to Fig. 1 of a fourth embodiment;

Fig. 11 is a sectional view on the plane 11-11-11-11 indicated in Fig. 10;

Fig. 12 is a section on the line 12-12 of Fig. 11; 5
Fig. 13 is a semi-diagrammatic view of a fifth embodiment, and

Fig. 14 is an exploded view of a pair of core sections as used in Fig. 13.

In the embodiment herein disclosed there is 10 illustrated in Figs. 1 to 5 inclusive a helical resistance coil of continuously variable resistance and practically unlimited maximum resistance constructed in accordance with the invention mounted on a supporting base 20 of any convenient construction. A metal bar mounted on the base 20 and of uniform cross section, here shown as substantially rectangular in section but which may be of circular, oval or any other desired form in this respect, is formed into a uniformly helical core support 21. Upon this support is positioned in end abutting sequence a series of preformed twisted toroidal sleeves 22 of electrically insulating material such as a pre-molded and baked ceramic paste, premolded 25 bakelite, vulcanite, etc. to form with the support 21 a continuous core of potentially unlimited extent and occupying a relatively small volume of space in proportion to the extent of surface available to be wound with a conductor. Each of the sleeves 22 may be preformed as a complete unit axially perforated to fit the bar 21 and may then be slid into place over the bar since the curvature of the latter in the case now under consideration is uniform in all directions. It seems to be preferable in practice, however, to premold each such sleeve 22 in two interlocking matched halves as shown best in Fig. 3 which may be applied directly to the bar 21 at the point of their permanent location. These half sleeves may be cemented or otherwise attached directly to the bar when in place although in general this is not advisable on account of the difference between the thermal coefficients of expansion of the two materials.

A winding 23 of wire of appropriate metal or alloy as for example nichrome is positioned on the compound core as above formed, the surface of which may be formed with a preformed spirally encircling groove to retain the turns of the winding in place. The winding extends around and along the core from a convenient point at or near one end thereof any desired distance to a second convenient point on the core where the winding may terminate and its end be fastened 50 55

in any convenient fashion. This winding 23 may be put in place in any convenient way. If the insulating sleeves 22 of the core are preformed axially perforated and transversely whole toroidal tubes, each such sleeve may be wound individually before being put in place on the bar 21 with an independent section of the winding, the adjacent ends of juxtaposed sections of the winding being subsequently united by any approved means such as welding or soldering after each sleeve has been slid into place along the bar. If the sleeves be formed of interlocking matched half sleeves, a length of wire for a section of the winding might be wound into a coreless helix a trifle larger than the core, then slid down over the completed core into position thereon, welded terminally to the preceding section of wire and drawn tautly into place on the core. In some cases the wire 23 might be wound directly on the completed core.

When the winding 23 is finally in place, one end of the winding is connected to a convenient binding post 24 or other terminal of any approved type, and if it be intended to use the coil as a fixed value resistance, the other end of the winding may also be connected to a second terminal. If desired the coil may further be tapped at points intermediate its ends and leads brought out to other terminals to enable the use of any desired fixed fractional part of the winding.

A fixed value resistance coil thus constructed is simultaneously strikingly compact and well ventilated. A great length of winding is disposed within a relatively small volume of space; the winding is securely supported over its entire length; and all points of the winding are freely exposed to afford efficient removal of heat by atmospheric convection as well as by direct radiation. The coil can therefore be used without damage under unusually heavy loads.

If the coil is to be used as a continuously variable resistance, the intermediate taps to terminals may be omitted and a sliding contact member provided to run along the coil. As disclosed and to this end a square metal shaft 28 is located in the axis of the helical core and rotatably mounted in the frame 20. A centrally correspondingly perforated metal block 30 slides snugly but easily on the shaft and is held in electrical contact with the shaft by a spring member 31 located in a corresponding groove in the block and pressing against the shaft. A duplex, resilient contact member 32 is rigidly attached to one side of the block 30 and is formed with a pair of integral complementary resilient guide and contact arms 33 which press against the wound core at opposite sides thereof and so make contact with the winding 23. Thus the winding at its contact with the arms 33 is electrically connected through the arms 33, the block 30 and the shaft 28 with a terminal 34 connected to the shaft in any convenient manner. The shaft 28 is further provided with a knob or handle 35 and, if desired, an indicating device may also be associated therewith. This device may comprise a spirally slotted dial plate 36 appropriately marked with a scale and an indicator 37 mounted to slide freely in the slot of the dial and also in a fixed radial guide 38 mounted under the dial on the base 20.

When the shaft is caused to rotate the block 30 rotates with the shaft thereby causing the arms 33 to slide along the helix rotationally. Due to the screw form of the helix this will in turn cause the block 30 to slide correspondingly on the shaft 28. Thus all points of the coil may be

traversed continuously by the contact arms 33 and hence the portion of the coil electrically interposed between the terminals 24 and 34 is continuously variable at will.

For some purposes it may be desirable to have the core substantially completely composed of dielectric material only. Such a modified embodiment of the invention is disclosed in Figs. 13 and 14. In this case, if the core 40 be helical, it is composed of identical, twisted, semi-circular, 10 toroidal segments 41 which may interlock at abutting ends by means of a square mortice 42 and tenon 43 as indicated in Fig. 14. This embodiment also illustrates a construction in which the interior of the helical coil is left entirely free of 15 access for convection air. The coil itself as a whole is rotatably mounted on end supports 44 journalled in a frame 45 and the sliding contact member 46 is carried on a fixed bar 47 outside of 20 and parallel to the helix.

Again it may be desirable to limit the dimensions of the apparatus in one direction while extending it in both directions at right angles thereto. In this case as in the modified form illustrated in Figs. 6 and 7, the core 51 instead of 25 being coiled on a helical axis may be confined substantially to one plane and coiled with its axial line forming a flat spiral. The core may now be constructed generally as in either of the two constructions already described, i. e. with or 30 without a metallic backbone inside of the dielectric component segments. But in either form the segments of the core will no longer be identical in form since the curvature per unit length of the spiral decreases from the inner end of the 35 spiral outwardly. Also the mechanism to carry the sliding contact must be modified since the radial distance of the block from the center around which it revolves is also variable when the contact moves along the spiral. Hence, as shown, 40 in this instance the contact block 52 may be carried by and slide along a radial conducting arm 53 pivoted at the center of the spiral.

A form is illustrated in Figs. 8 and 9 in which provision is made for maximum freedom of access for convection air to all parts of the coil with minimum mutual interference of convection currents. In this instance the axis of the core 60 takes the form of a three dimensional conchoid, the path of a point revolving in a conical 45 surface and moving away from its apex. Here the sliding contact 61 is carried by and slides on a rod 62 pivoted and movable to describe the surface of a cone parallel to the general form of the coil. As in the case of the flat spiral last described, the core may be with or without a metal backbone and the core segments, while generally 50 mutually similar are not mutually identical being of varying principal curvature. As indicated in Fig. 9, the conchoidal element 60 may be 55 mounted within a cage or skeleton support 63 having a disk 64 rotatably mounted in one end thereof to act as a supporting guide for the handle end of the contact slide rod 62.

It may be noted that in each case a characteristic feature of the structure is that the segments of the core form a non-self-terminating sequence of substantially toroidal sections. In the case of the helix the core does not return upon itself or close because each of the segments of the core 70 is of double curvature although the curvature in both directions is constant. In the flat spiral it is because although the segments are only singly curved, their curvature diminishes outwardly from the center of the spiral; while in the con- 75

choid the segments are not only doubly curved but their curvature diminishes in both directions outwardly from the apex of the cone enveloping the conchoid.

8 In the case of the flat form of Figs. 6 and 7, or of the conchoidal form of Figs. 8 and 9, if the core follow a logarithmic spiral, equal angular turns of the radial arm will alter the resistance value between the terminals by proportionately 10 equal increments; whereas in the helical form of Fig. 1, equal angular turns of the knob represent equal additive increments of resistance. The form of the core may thus be easily shaped to cause the relation between angular turn of 15 the actuating member and resultant change in resistance to assume any one of a variety of mathematical functional forms, a matter of considerable value in making a resistance with an arbitrarily graduated scale for inclusion in a 20 Wheatstone bridge, Kelvin bridge, etc., as part of any one of an infinite variety of testing devices.

Although thus far principally disclosed as embodied in a resistance coil, the invention is not 25 confined to such. Figs. 10, 11 and 12 disclose a variable condenser made in accordance with the invention. A curvilinear core is formed and composed similarly to the cores previously described of segments 78 of insulating material threaded 30 on a supporting metal or non-metallic and insulating inner support 71 carried on a base member 72. Condenser elements 73 are positioned between the segments 78 and have alternate interior and exterior terminals 74 and 75 respectively. The condenser elements 73 may comprise 35 single conductive plates between the segments 78, or as herein disclosed may each consist of a group of interleaved conductive and insulating laminae. The exterior terminals 75 are permanently connected together by a conductor 76 40 connected to a terminal 77. A tubular metal shaft 78 is slidably mounted in the base 72 to be reciprocable within the helical core and is so proportioned as to make wiping contact with 45 each of the terminals 74 in succession as the shaft advances along the axis of the helix. A terminal 78 is electrically connected to the shaft.

It will be evident that a common feature of 50 the several embodiments described is the fact that the core is not self limiting or self terminating since it has in general the form of a non-re-entrant or open coiled curve as distinguished from cores having the general form of a circle, oval, square, oblong or the like. A second common characteristic is that each core is built up 55 of a coiled sequence of axially curved segments

which are either alike or similar in shape. Thus it is possible to build up in relatively small space an apparatus of the kind referred to of practically unlimited capacity and with all of its parts conveniently and freely accessible.

It will be further evident that the embodiments herein disclosed are illustrative merely and may be widely modified and departed from without departing from the spirit and scope of the invention as pointed out in and limited solely 10 by the appended claims.

What is claimed is:

1. In an electrical apparatus, a curved non-self-limiting core comprising component arcuate segments of continuously varying curvature 15 joined together end to end in a sequence whose axis has the general form of a curve selected from the class of curves consisting of three dimensional conchoids and flat spirals.

2. In an electrical apparatus, a curved non-self-limiting core comprising component axially 20 arcuate segments of continuously varying double curvature joined together end to end in a sequence whose axis has the general form of a a three dimensional conchoid.

3. In an electrical apparatus, a curved non-self-limiting core comprising component axially 30 arcuate segments of continuously varying curvature joined together end to end in a sequence whose axis has the general form of a curve selected 35 from the class of curves consisting of three dimensional conchoids and flat spirals, a conductive member carried by the core, and a contact member slidable along the conductive member.

4. In an electrical apparatus, a curved non-self-limiting core comprising component axially 40 arcuate segments of continuously varying double curvature joined together end to end in a sequence whose axis has the general form of a three dimensional conchoid, a conductive member carried by the core, and a contact member 45 slidable along the conductive member.

5. In an electrical apparatus, a core comprising component axially arcuate segments of continuously and uniformly varying double curva- 50 ture joined together end to end.

6. In an electrical apparatus, a core comprising component axially arcuate segments of continuously and uniformly varying single curvature joined together end to end.

7. In an electrical apparatus, a core comprising component axially arcuate segments of continuously and uniformly varying curvature joined together end to end.

ERWIN E. FRANZ. 55
